UNITED STATES PATENT OFFICE.

RICHARD P. McCOLLUM, OF PHILADELPHIA, PENNSYLVANIA.

PAD FOR A HERNIAL TRUSS.

1,158,139.

Specification of Letters Patent. Patented Oct. 26, 1915.

Application filed January 5, 1915. Serial No. 562.

To all whom it may concern:

Be it known that I, RICHARD P. McCOLLUM, a citizen of the United States, residing in the city and county of Philadelphia, 5 State of Pennsylvania, have invented a new and useful Pad for a Hernial Truss, of which the following is a specification.

My invention consists of a pad for a hernial truss the same being composed of a 10 pliable body, a headed thimble, and a securing member which latter is adapted to pass through the waist-belt into said thimble for connecting the pad in position, the head of said thimble being adapted to rest against a 15 portion of said body and contact with direct pressure against the abdomen at the afflicted place, while said body is adapted to close around said afflicted place without severity and prevent shifting of the pad.

20 The invention is satisfactorily illustrated in the accompanying drawing, but the important instrumentalities thereof may be varied, as long as they are included in the scope of the claim.

25 Figure 1 represents a perspective view of a hernial truss embodying my invention. Fig. 2 represents an elevation of a portion thereof taken from the inside. Fig. 3 represents a longitudinal section thereof on line 30 α — α Fig. 2. Fig. 4 represents a longitudinal section of the pad carrying plate in normal condition.

Similar numerals of reference indicate corresponding parts in the figures.

35 Referring to the drawings, 1 designates a plate formed of steel or other suitable material of resilient nature, it being preferably straight or right lined in normal condition, as illustrated in Fig. 4. In said plate in the 40 longitudinal direction thereof are the elongated openings or slots 2, which are three in number side by side in said direction, either the right or left one of which is adapted for the connection with the plate of a pad for a 45 single hernia, or the two which are in opposite side portions are adapted for the connection with the plate of a plurality of pads for double hernia. The central slot is adapted for the connection with the plate of an umbilical pad, which latter may be centered on the umbilicus or adjusted sufficiently to the right or left thereof to more or less extent, while contacting with the umbilical according to the condition of the latter.

55 The pad 1 in normal condition is laid flat

upon the waist belt 3 at a proper place thereon and firmly secured thereto by rivets 4, or other suitable means, there being interposed between the plate and belt the washers 5 of leather or other suitable material. A similar washer 6 is applied to the inner facing of the belt 3 back of the washer 5, thus strengthening the belt at the opposite places and adding to the wearing qualities thereof, both washers having slots or openings there- 60 in registering with those in the plate 1.

7 designates one of the pads employed, it being composed of the hollow annulus-shaped inflatable body 8 of soft rubber, the tubular thimble 9 which is passed through the central opening of said body, the bore of said thimble being screw-threaded, and the head 10 on the inner end of said thimble, said head resting against the central portion of the body 8 around the opening thereon, 70 and having its outer face sufficiently convex for the purpose intended, said head being formed of rigid material preferably hard rubber and is adapted to be fitted against the human body at or about the afflicted part 75 thereof. In order to hold the said head 10 and the thimble 9 engaged with the body 8 and consequently connect the pad with the belt 3, I employ the screw 11 whose shank passes through the proper slot of the 80 plate 1 and those of the washers 5 and 6, its head bearing against the plate 1 about the wall of the slot therein, so that when said screw is tightened it draws the thimble and 85 head of the latter in position on the body 8 and compresses the latter to a required extent and holds said body and consequently the pad securely on the belt, it being evident that the pad may be adjusted to the right or left according to requirements, it being seen 90 that when the pad is presented to the human body at the afflicted place, and the belt is fitted on the waist and drawn up, the plate 1 flexes and so curves around said place causing a direct pressure against the afflicted place, thus controlling the hernia with sufficient firmness and yet without severity, while the body 8 closes against the afflicted place around that occupied by the head 10, thus serving to prevent shifting of the hernia from the position engaged by the head 10. 95

100 It is evident that when the pad is presented to the desired place and the belt adjusted, the latter curves around the abdomen and so 105

- flexes the plate that it also assumes a curved form, and is converted into a well defined spring which imparts pressure against said plate in the manner stated, and continues the 5 same as long as the belt is retained on the body of the wearer, but when said belt is removed therefrom the plate resumes its normal straight or right lined shape ready when again applied in position to be flexed or bent 10 in curved direction as before, and the resultant pressure may be adjusted by correspondingly tightening the belt.
- Having thus described my invention what I claim as new and desire to secure by Letters Patent, is:—

Copies of this patent may be obtained for five cents each, by addressing the "Commissioner of Patents, Washington, D. C."

A truss pad composed of a hollow, inflatable body of the form of an annulus, a thimble adapted to enter the opening of said body, a head on said thimble adapted to be seated on said body around the wall of said opening, and a screw which is adapted to enter said thimble and be engaged with a portion of a belt employed for the truss. 20
